UNITED STATES PATENT OFFICE.

ANDREW DAHLENE, OF SAN DIEGO, CALIFORNIA.

MULTIPLE OIL-GAS GENERATOR AND DISTRIBUTOR.

Application filed July 25, 1921. Serial No. 437,536.

To all whom it may concern:

Be it known that I, ANDREW DAHLENE, a citizen of the United States, residing at San Diego, in the county of San Diego and State of California, have invented a new and useful Multiple Oil-Gas Generator and Distributor, of which the following is a specification.

This invention comprises a device for vaporizing liquid fuel such as gasoline, kerosene and the like and distributing it to points of use, and an object is to provide a cheap and simple appliance that will effectively and satisfactorily vaporize such fuels and distribute the vapor to numerous burners.

Other objects are durability and easy operation and cleansing.

The invention is broadly new, basic, and pioneer in that the jet piece is combined with a vaporizing tube, an air mixer and a pressure chamber connected to the air.

Other objects, advantages and features of invention may appear from the accompanying drawing, the subjoined detail description and the appended claims.

The accompanying drawing illustrates the invention.

Figure 1 is a broken diagrammatic plan on a small scale, of an apparatus embodying this invention, with parts arranged as adapted for use in a range.

Fig. 2 is a diagrammatic plan similar to Fig. 1, with the gas burner arranged in a line commonly adapted for cooking at a counter not shown.

Fig. 3 is an enlarged fragmental detail of parts of the apparatus shown in Figs. 1 and 2.

Fig. 4 is a section on line x^4 , Figs. 1 and 3.

Fig. 5 is a section on line x^5 , Fig. 4.

Fig. 6 is a cross section on line x^6 , Figs. 1, 3 and 4.

1 is a generating tube, and 2 a distributing head. The tube 1 is supported above the distributor head 2 by brackets 3, 4 secured by stud bolts 5 to said head.

The tube 1 has a threaded end 6 that is connected to a pipe fitting 7 which is connected to the valve 8, of a fuel supply pipe 9 that leads from a source not shown and delivers the fuel under pressure to the tube 1.

The tube 1 is for vaporizing and gasifying liquid fuel, and the distributing head 2 is for receiving and distributing the products from the tube. Said head comprises a top plate a , an annular bottom plate b , an

inner annular wall c , connecting said plates a and b , an outer annular wall d extending between and connected to said plates a , b and provided with an outwardly extending tubular inlet and air mixing neck e and with lateral distributing orifices f ; there being, in the instance shown, six of said orifices, equally disposed on the opposite sides of the neck and inner annular wall c . Said head is a single casting and its purpose is to receive fuel products and air through the tubular neck e and to allow it to impinge against the inner wall c and to be directed thereby and caused to be thoroughly mixed in the annular passage and directed to issue through the orifices f as occasion may require.

The outlet end 10 of tube 1 forms a gas tight fit in the socket 11 of the jet-piece casting 12 and is held from rotary or longitudinal movement therein by a set screw 13 and is provided with a reduced port 14 held in register with the bore 15 of stem 16 of the jet piece which comprises the valve casting 17 for needle valve 18 that controls the nozzle 19, from which the fuel products are directed into the air mixing passage 20 that opens into an annular chamber 21 in head 2.

In the top wall of head 2 is a port 22 that leads from annular chamber 21 into an elongated auxiliary vapor and gas distributing chamber 23 that is formed by an inverted elongate trough or hollow cap 24 secured to the top of head 2 by stud bolts 25.

Trough 24 is provided with slits 26 through which vapor escapes from chamber 23 up around tube 1 and is there ignited to heat said tube to vaporize liquid fuel therein.

The auxiliary heater comprises a wall 27 integrally connected with and extending upward from the top of head 2; and spaced from and surrounding the inverted trough 24, so that between them there is formed a rectangular channel 28. Said channel is partly filled with an absorbent non-combustible material, as asbestos and is adapted to receive a priming charge of alcohol,

which, when ignited, burns for a sufficient time to heat tube 1 so as to volatilize the liquid fuel therein. The vapor discharges from nozzle 19 with sufficient force to cause a current of air to flow through the mixing passage 20 into annular chamber 21 where there is a thorough mixing of air and vapor to form a combustible gas. Part of the

5 mixture passes through port 22 into auxiliary chamber 23, and from there discharges through slits 26 into the alcohol flame where it is ignited to automatically continue 10 vaporizing or gasifying the liquid fuel in tube 1 so long as valve 8 remains open and the fuel supply is unexhausted.

15 The major portion of the gas thus formed is distributed from the annular chamber 21 through pipes 29 to gas burners 30 that can be arranged in any desired manner either to surround the vaporizer as shown diagrammatically in Fig. 1 for use in cooking ranges; or such pipes can be off-set and aligned as 20 shown in Fig. 2 for use along a counter.

25 It is understood however that my appliance is adapted to other purposes than distributing gas for cooking ranges and heaters and reservation is made to all such uses as 30 do not depart from the scope and spirit of the invention.

35 To aid in vaporizing the liquid fuel entering tube 1, I insert in the tube a solid cylindrical stick of carbon 31 that is of somewhat 40 less diameter than the tube, so that the vaporizing passage is crescent shaped embracing the top sides and major portion of the bottom of the carbon cylinder so that any liquid in the passage will be subjected 45 in thin layers to the most intense heat and the vaporized fuel will be subjected to a less direct heat; thus avoiding cracking of the hydro-carbon.

45 Preferably the carbon stick has sharp 50 tapered ends 32 so that liquid fuel discharging under pressure from the opening 33 in pipe fitting 7 and striking the end of the carbon, will be broken up into a fine spray that is directed outward against the inside 55 of tube 1.

55 The carbon stick 31 accumulates considerable heat so that the spray of liquid fuel broken up by its pointed end 32 flows on between two highly heated surfaces so that it 60 will quickly volatilize and gasify.

65 In case the tube needs cleaning the casting 12 is detached and the tube 1 is detached from the fitting 7, after which the carbon stick 31 and any accumulations therein are 70 removed. The carbon stick may then be immersed in a cleansing fluid that will remove the accumulations without affecting the carbon stick.

75 In practice, when parts are assembled as described the porous material is charged with alcohol or the like, and valve 8 is opened to permit liquid fuel to discharge into tube 1 by gravity or other pressure, and the alcohol is ignited in channel 28 to heat tube 80 1, and thereupon the heated gas or vapor discharges under pressure through nozzle 19 into the distributor head 2; after which part of this discharged vapor passes through the port 22 into auxiliary chamber 23 and 85 through slots 26 to tube 1 and is ignited by

the initial flame from the alcohol as hereinbefore described.

90 The amount of fuel allowed to become vapor is regulated by valve 8; and the vapor or gas discharged to head 2 is regulated by valve 18. The distributor pipes 29 leading from distributor head 2 to burners 30 are supplied with valves 33; so that the gas or vapor can be directed to any one or all 95 of the burners 30 as is desired. 75

Particular attention is directed to the distributor 2 which as shown consists of two concentric annular walls *c, d* united.

I claim.

1. A device of the character set forth 80 comprising a tube; a multiple distributor head arranged under said tube and having an annular chamber; a cap secured to said head and forming an auxiliary vapor chamber that is connected by an opening to the annular chamber of said head, and that has openings adjacent said tube; a liquid supply pipe connected to said tube; a nozzle connected to said tube and adapted to discharge vapor into said annular chamber; a needle valve for regulating the discharge of vapor from said nozzle; pipe connections from said multiple distributor head adapted to be connected to vapor burners; valves in 85 said pipes; and an auxiliary heater attached to said multiple distributor head for the purpose specified. 90

2. A device of the character set forth 100 comprising a distributor head having a chamber formed by a top plate, a bottom plate, and an inner annular wall connecting said plates; said head having an inlet and distributing orifices; a tube supported by said head; means secured to said head to form an auxiliary chamber, said chambers being in communication with each other, and said auxiliary chamber being adapted to discharge vaporized fuel therefrom to 105 heat said tube.

3. A device of the character set forth 110 comprising a distributing head having a chamber, a hollow cap secured to said head and therewith forming an auxiliary chamber, there being a port connecting said chambers; a tube adapted to be connected to a fuel supply; and a nozzle connected to said tube and adapted to discharge into the chamber in the distributing head; said auxiliary chamber having slits adapted to discharge vaporized fuel to support a flame 115 120 for heating said tube.

4. A device of the character set forth 125 comprising a tube adapted to be connected to a fuel supply; a distributor head; a nozzle attached to said tube and adapted to discharge products from said tube into said head; and an auxiliary chamber adapted to receive products from said head and discharge such products to heat said tube.

5. A device of the character set forth 130

- comprising a tube adapted to be connected to a fuel supply; a distributer head; a nozzle attached to said tube and adapted to discharge products from said tube into said head; an auxiliary chamber adapted to receive products from said head and discharge such products to heat said tube; and an auxiliary heater spaced from and surrounding the auxiliary chamber. 5
- 10 6. A device of the character set forth comprising a tube adapted to be connected to a fuel supply; a distributer head; a nozzle attached to said tube and adapted to discharge products from said tube into said head; an auxiliary chamber adapted to receive products from said head and discharge such products to heat said tube; and a carbon stick in said tube to form a crescent shaped chamber for the purpose specified. 15
- 20 7. A device of the character set forth comprising a tube, a multiple distributor head under said tube, burners; pipes connecting said head with said burners, means connected with said head for heating said tube, and a solid carbon stick in said tube for the purpose specified. 25
- 30 8. A device of the character set forth comprising a tube, a multiple distributor head under said tube, burners; pipes connecting said head with said burners, means connected with said head for heating said tube, and a carbon stick in said tube to 35
- form a crescent shaped chamber as and for the purpose specified. 40
9. A device of the character set forth comprising a tube; a multiple distributor head arranged under said tube and having an annular chamber, a hollow cap secured to said head and therewith forming a chamber that is connected by an opening to the annular chamber of said head; said cap having openings adjacent said tube, a supply pipe connected to said tube, a valve in said supply pipe, a nozzle connected to said 45 tube and adapted to discharge vapor into said annular chamber, and an auxiliary heater attached to said head for the purpose specified. 50
10. A device of the character set forth comprising a tube adapted to be connected to a fuel supply; a distributer head; a nozzle attached to said tube and adapted to discharge products from said tube into said head; an auxiliary chamber adapted to receive products from said head and discharge such products to heat said tube; and a carbon stick in said tube to form a crescent shaped chamber for the purpose specified; said stick having sharp tapered ends. 55

In testimony whereof, I have hereunto set my hand at San Diego, California, this 18th day of July, 1921.

ANDREW DAHLENE.
